UNITED STATES PATENT OFFICE.

CHARLES AUGUST DEUSCHER, OF NEW YORK, N. Y.

ELECTRIC CONNECTION.

Application filed July 20, 1920. Serial No. 397,719.

To all whom it may concern:

Be it known that I, CHARLES A. DEUSCHER, a citizen of the United States, and a resident of the city of New York, borough of Bronx, in the county of Bronx and State of New York, have invented a new and Improved Electric Connection, of which the following is a full, clear, and exact description.

10 This invention relates to electrical conductors and has particular reference to a method and apparatus for connecting such conductors.

An object of the invention is to provide a 15 simple and ready method whereby electrical conductors may be connected firmly and in a permanent manner without the use of solder.

Another object of the invention is to provide 20 an apparatus whereby electrical conductors to be connected may be joined by a strong, compact metallic link without the use of solder and by the use of a minimum number of parts and appliances.

25 Still another object resides in the provision of the particular construction and arrangement of parts as will hereinafter be described and claimed and shown in the accompanying drawing.

30 The invention comprises in general the insertion of an end of the wire into a metallic sleeve which is then pressed around the wire on all sides by the application of uniform pressure thereto from all sides. The 35 end of the wire may be straight, but in some instances it is preferable to give it a twisted, corrugated, or uneven outline or configuration. This appearance may be given the wire by twisting it or bending it back on 40 itself.

The invention further comprises the provision of the ends of conductors, to be connected, with a series of indentations or grooves, or the roughening of the end surfaces, and the union of adjacent surfaces to be connected, when so prepared, by compressing around the abutting end surfaces a metallic link or sleeve by the application of uniform pressure on said link or sleeve from 45 all directions simultaneously so that the compression of the link or sleeve on to the ends of the conductor is uniform throughout its length and from all sides thereof.

50 This process and this apparatus do not 55 require the use of solder to effect a simple,

compact and exceedingly strong and permanent union.

This invention is equally applicable to the union of one wire to a terminal plate or other element without relation to its connection to another conductor.

The invention is shown in the drawing, of which—

Figure 1 represents a sectional view showing the ends of the conductors and the intervening link or sleeve in position ready for the compression of the link thereon;

Figure 2 is a sectional view showing the parts after the compression has taken place;

Figure 3 is a sectional view representing the use of a different form of conductor end;

Figure 4 represents a modified form of terminal plate or lug; and

Figure 5 represents a partial section of the modification shown in Fig. 4.

As shown in the drawing, Figure 1 represents the application of my invention to the union of two wires 1 and 2 the ends of which are to be suitably mechanically and electrically connected without the use of 80 solder to form a firm, strong, permanent joint. In the form shown in Figure 1, the end of each wire is bent back upon itself and twisted in the form of a spiral as shown. These twisted end portions are 85 then inserted within opposite ends of a connecting link or sleeve 3, which may be of any suitable metallic conducting material but which is preferably made of copper. This link or sleeve 3 is then compressed around the abutting and adjacent ends of the conductors to be connected, by any suitable means which will, during the compression, exert pressure on the link from all directions equally and simultaneously 90 95 around its peripheral surfaces, so that the link is compressed or swaged on to the conductor ends uniformly. As a result of this compression, I have formed a union, such as shown in section in Figure 2, which is exceedingly strong and durable, and one which has been so made without the use of solder.

In the case of heavier wires, it may not be advisable to form the spiral twists there-in as shown in Figure 1. In these cases it is found better to provide the ends of the wires with a roughened portion which may be produced by a file or by producing there-on a plurality of grooves 4 by the use of a 100 105 110

suitable tool. These grooved end portions of the wires are then inserted in a link or sleeve as above mentioned and are joined together in a manner exactly similar to the 5 union of the wires supplied with respect to Figures 1 and 2.

This invention is equally applicable to the union of a single wire to a terminal plate, such as represented by the numeral 5 10 in Figure 4. The terminal plate 5 may be adapted for connection with binding posts and have at one end thereof a sleeve portion 6 which can be placed around the end of the wire to which it is to be connected and compressed thereon in the manner above described. The end of the wire thus connected to the terminal plate may be prepared in either of the ways above mentioned, either by producing a spiral twist therein or by 15 forming grooves or roughened portions on its end surface, or in any of the other above mentioned ways.

It is apparent, therefore that I have produced a simple, compact and exceedingly 20 strong union of electrical conductors, or of 25 a conductor with a terminal plate, without

the use of solder. I have found these unions to be exceedingly permanent and to be capable of standing up under the application of severe stresses longitudinally thereof. 30

What I claim is:

1. A method of applying a sleeve connection to an electrical conductor which comprises spirally twisting the end of the conductor back upon a portion thereof to form a twist, inserting said twisted portion within one end of the sleeve, and compressing the sleeve on the end of the conductor by the application thereto of pressure uniformly and simultaneously from all directions. 35 40

2. An electrical connection comprising a conducting sleeve, an electrical conductor having an end portion bent back on itself in the form of a spiral twist, said end portion inserted into one end of said sleeve, said sleeve being compressed upon said twisted end portion to make a tight mechanical union between the sleeve and the end portion of the conductor. 45

CHARLES AUGUST DEUSCHER.
